ABSTRACT OF THE DISCLOSURE

A hand puppet construction comprising opposed plastic sheets which are heat sealed together at their adjoining edges. Printing is formed on at least one of the sheets with the printing material being located on an interior facing surface. To insure complete sterilization so that the construction can be directly associated with food products, the constructions are packed in containers and then exposed to a gaseous sterilizing atmosphere to insure the destruction of contaminants.

This invention relates to hand puppet constructions and to methods for producing the constructions.

Hand puppets have been manufactured for many years for use as toys, and in recent years, such puppets have been formed of heat sealable materials. When such materials, for example polyethylene, are used for manufacturing puppets, then large numbers of the puppets can be manufactured at a very low cost.

In view of the fact that very large numbers of plastic hand puppets can be manufactured at low cost, the puppets are very suitable for use as premiums. Thus, manufacturers can well-afford to purchase large numbers of the puppets, and associate them with their products to add to their sales appeal.

The hand puppets are especially appealing when various figures, for example cartoon characters, are printed directly on the plastic material. This makes the puppets especially appealing to children and provides a further incentive for manufacturers to purchase the puppets for use in association with their products.

A significant difficulty has arisen when attempts have been made to market the puppets for use in association with food products. In view of government regulations, prior puppet constructions could not be directly associated with a food product (for example, inserted inside a cereal package) in view of the danger of contamination. Contamination can occur because of handling, however, this can be controlled to a large degree. A more significant problem exists because printing materials employed for providing designs are considered to be potentially dangerous and puppets having such printing materials could not be brought into direct contact with food.

It is a general object of this invention to provide an improved hand puppet construction formed of plastic material.

It is a more specific object of this invention to provide a hand puppet construction which can be economically manufactured in large volume, which can be printed to provide caricatures or other material on the constructions, and which are designed and processed so that contamination due to handling or because of the presence of printing material can be avoided.

These and other objects of this invention will appear hereinafter and for purposes of illustration but not of limitation, specific embodiments of the invention are shown in the accompanying drawing in which:

FIG. 1 is a front elevational view of a puppet construction characterized by the features of this invention;

2

FIG. 2 is a rear elevational view of the puppet construction;

FIG. 3 is an elevational view of the construction shown in association with a hand; and

FIG. 4 is a schematic illustration of a system employed for sterilizing puppet constructions.

The construction of this invention generally comprises opposed plastic sheets which are heat sealed together at their adjoining edges with a caricature or other material printed on at least one of the sheets. All of the printing ink is located on an interior facing surface of the sheet; however, transparent plastic is employed so that the printing is visible from the exterior of the construction. The material is printed in reverse fashion on the interior surface of the sheet so that a right reading image will be visible when the puppet is in use.

In the production of the puppet constructions, a pair of plastic sheets are printed in the desired fashion, and the sheets are then brought together so that all of the printing material is located on interior facing surfaces. The sheets are then die cut to conform to a hand puppet configuration, and the sheets are heat sealed at their adjoining edges.

In order to insure that the puppets will be uncontaminated, sterilization is preferably carried out. A preferred arrangement involves the packing of the constructions in shipping containers, and the exposure of the containers to a gaseous sterilizing atmosphere. The sterilizing gas will penetrate the containers for contact with the surfaces of the puppet constructions. This represents a preferred sterilizing arrangement since the constructions can then be delivered to the user without reopening the containers whereby further handling by the manufacturer can be completely avoided. The user of the puppets, for example a food manufacturer, can then employ standard equipment for removing the constructions and for inserting the constructions in food containers without the need for further handling.

The puppet constructions shown in the drawings play a caricature 10 which is visible through the front of the construction. The construction is formed of a pair of sheets 12 and 14 which are heat sealed at their adjoining edges.

In the manufacture of the constructions, the caricature 10 and the wiring shown at 16 are printed on the interior face of the sheet 12. If desired, multiple colored printing may be employed. In addition, a background 18 may be printed over the caricature 10 so that the caricature will not be distinctly visible when viewed from the interior face. Since the plastic material forming the construction is transparent; however, the caricature will be clearly visible when viewed from the exterior face, and the background 18 will substantially avoid the appearance of the individual hand. A similar non-transparent background 20 may be applied on the interior surface of the sheet 14 so that the back of the user's hand will not be visible.

It will be noted that the printing on the inner face of the sheet 12 is reversed so that a right reading image is presented when the puppet is in use. The printing mechanisms can be readily adapted for providing reverse printing in the manner shown.

FIG. 3 shows the construction in use. The hand of the user is inserted through an opening 22 which is provided by cutting off the strip 24 along the bottom edge of the construction. A line 26 may be printed on the interior face of one of the sheets 12 or 14 to provide a guide for cutting. With this arrangement, the sheets 12 and 14 are sealed at all adjoining edges so that the construction is completely closed prior to use.

By providing printing on the interior surfaces in the manner described, contamination problems can be com-

pletely eliminated insofar as printing materials are concerned.

To avoid contamination which might result because of handling, the constructions are preferably packed in shipping containers 28 and then located in a chamber 30 as shown in FIG. 4. The chamber 30 is connected to a tank 32 which contains a sterilizing gas such as ethylene oxide or propylene oxide. This gas is introduced into the chamber through line 34, and thus brought into contact with the containers 28. The gas will penetrate the containers and come into direct contact with the constructions included therein.

An outlet pipe 36 is provided particularly if the gases are to be circulated during the sterilizing operation. An exhaust line 38 is provided for purposes of evacuating the chamber 30 prior to a sterilizing operation. Reference is made to Pat. No. 2,938,766 for a more detailed explanation of the manner in which a sterilizing process of the type described can be carried out.

In a typical manufacturing operation, continuous sheets of plastic material, for example polyethylene, will be passed through printing apparatus to provide the desired caricatures and background. The sheets are then brought together with all of the printing systems being located on the mating interior surfaces of the sheets. A die cutting tool, which is preferably a heated blade, is then brought into contact with the mated sheets to provide the hand puppet configuration. A heated die cutting tool is employed so that heat sealing at all adjoining edges of the sheets will be carried out simultaneously with the die cutting operation.

The printing, die cutting, and heat sealing operations can be carried out on a continuous basis whereby the constructions can be economically manufactured in large numbers. Thus, the reverse printing operation does not create insurmountable problems insofar as economical production is concerned. Similarly, the sterilization procedure described will handle large volumes of the constructions and, therefore, the constructions can be offered for use in conjunction with food products at a reasonable cost.

It will be understood that various changes and modifications may be made in the above described system which provide the characteristics of this invention without departing from the spirit thereof particularly as defined in the following claims.

That which is claimed is:

1. A method for the production of a hand puppet construction comprising the steps of providing a pair of plas-

tic sheets, printing a figure on at least one sheet, die cutting said sheets to conform to a hand puppet configuration, locating said sheets in opposed relationship with the printing substance having an interior facing relationship in the assembly of opposed sheets, heat sealing the opposed sheets at their adjoining edges, sterilizing the completed puppet construction to eliminate contamination on the exterior faces of the puppet constructions, the sterilizing comprising the steps of packing a plurality of puppet construction in a container, and exposing said container to a gaseous sterilizing atmosphere, said atmosphere penetrating the container for contact with the puppet constructions to thereby achieve sterilization.

5 2. A method in accordance with claim 1 wherein said die cutting is accomplished by means of a heated die with said sheets being located in said opposed relationship during the die cutting whereby heat sealing of the sheets occurs simultaneously with the die cutting.

10 3. A method in accordance with claim 1 wherein said printing step includes printing a cutting line on said interior facing surface of said one sheet adjacent the bottom edge of the construction whereby said construction is adapted to be cut along its bottom edge to provide an opening for insertion of the hand.
